UNITED STATES PATENT OFFICE.

CYRUS M. CARNAHAN, OF ALLEGHENY, PENNSYLVANIA, ASSIGNOR TO THE NATIONAL ROLLED STEEL CAR COMPANY, OF PITTSBURG, PENNSYLVANIA.

EQUALIZING DRAFT-GEAR.

SPECIFICATION forming part of Letters Patent No. 665,382, dated January 1, 1901.

Application filed February 28, 1900. Serial No. 6,887. (No model.)

To all whom it may concern:

Be it known that I, CYRUS M. CARNAHAN, a citizen of the United States, residing at Allegheny, in the county of Allegheny and State 5 of Pennsylvania, have invented certain new and useful Improvements in Equalizing Draft-Gear, of which the following is a specification, reference being had to the accompanying drawings, forming part of this specification, 10 in which—

Figure 1 is a longitudinal sectional view of the lower framework of a car and showing the application of my improved draft-equalizing apparatus. Fig. 2 is a similar view illustrating a modified construction. Fig. 3 is a 15 partial similar view showing a still further modification. Fig. 4 is a similar view where in the truss members do not cross at the middle, but are connected at points more adjacent to the truss. Fig. 5 is a perspective detail view showing the central rod clamping and supporting device.

My invention relates to the construction of railway and other cars; and it consists in the 20 application thereto of specially arranged draft-equalizing apparatus by which the pulling strain is equally distributed throughout the framing and with relation to the running-gear.

30 A particular object of the invention is to provide means for connecting the trucks with the main framework of the car in such a manner that the pulling strain of the draft-gear will be communicated to the running-gear, so 35 as to obviate the unequal strains thereon, and in general to provide a stiffer arrangement than heretofore, while at the same time permitting of the usual radial movement of the trucks with relation to the car-body.

40 Referring now to the drawings, 2 2 are the usual bolsters of the truck-frame, with which, by the king-bolt 3 and fifth-wheel 4, pivotal connection is made between the trucks and the main body portion of the car.

45 As usually constructed the pulling strain of the draft-gear is imparted to the trucks through the king-bolt only and by the mere action of gravity, and in such a connection, especially in cases of sudden movement or 50 jarring or on upgrades, the normal relation of the car-body to the trucks is disturbed, throwing an excessive strain on the king-

bolts and fifth-wheel and tending to permanently impair the efficiency of the various parts. To remedy this defect, I have provided a bracing mechanism consisting of longitudinal tension members, as rods 5, connected at one extremity to the framing-timbers of the car, as shown at points 6, which points are as remote as practicable from the 60 trucks to which the opposite ends of the tension members 5 are connected. These opposite ends of the tension members, as shown in Fig. 1, are joined by bolts or rivets 7 to a clevis 8, having an engagement with the king-bolt 3, 65 such arrangement permitting of free movement of the truck on curved tracks without exerting undue strain on the tension members. At any point in its length each of the tension members 5 is provided with a turn-buckle 9, by which it may be adjusted, the turnbuckles being preferably provided with lock-nuts 10 to prevent loosening. At a point 70 midway of the car, where the tension members cross each other, they are secured together by clamps 11, the rods being bent, as shown at 12, Fig. 4, or straight, if desired, so as to pass each other on the same plane, and the inner faces of the clamps, which consist of two side plates held together by bolts, 75 are provided with grooves 13, corresponding to the positions of the rods and adapted to provide suitable clearance therefor. This clamp is supported by an upwardly-projecting hook 14 in engagement with a cross-bar 80 15, incorporated with the framework, or in any other suitable or preferred manner. This construction provides a support for the tension members, prevents sagging, and adds stiffness to the entire construction by assembling the tension members and forms, in effect, a double-sided truss.

In Fig. 2 I have shown, in addition to the construction just described, supplementary tension members 16, connected to the clevis 95 8 at the opposite side, projecting upwardly and forwardly and attached to the framing-timbers at 17, these members also being provided with turnbuckles 9. These supplementary tension members 16 serve to impart movement directly from the forward end of the car to the forward truck and are of advantage and assistance as auxiliaries to the main tension members. In Fig. 3 the same arrange-

ment is illustrated, but attachment is made with the spring-board 18 of the trucks, thus obviating the necessity of attachment with the king-bolt.

- 5 It is to be noted that where the supplementary members 16 are employed their upper portions should be deflected laterally, so as to provide clearance for the draft-gear. By this construction it will be seen that the tension of the draft-gear will be imparted from the car-framing through the tension members directly to the trucks, thus rendering them independent of such transmission through the king-bolt.
- 15 In Fig. 4 the tension members do not cross each other, but are connected to the framing-timbers near the middle of the car, their operation and function being similar in all respects to the construction already described.
- 20 It will be understood that various changes and modifications in detail may be made without departing from my invention—as, for instance, by the substitution of other forms or constructions of the tension members or their
- 25 attachments for those which I have shown and described—and all such changes and variations I desire to include within the scope of the claims.

The advantages of my invention will be appreciated by those skilled in the art, as it provides a simple, cheap, and efficient remedy for a serious defect now present in the usual construction of this class of rolling-stock.

What I claim is—

- 35 1. Equalizing mechanism for cars consisting of rigid tension members secured at one end to the car-framing and at the other end to the under central portion of the truck, substantially as set forth.
- 40 2. Equalizing mechanism for cars consisting of tension members secured at their ends to the car-framing, and at their other ends to

the trucks, and crossing each other intermediate of their ends, substantially as set forth.

3. Equalizing mechanism for cars consisting of rigid tension members secured at one end to the car-framing and at the other to the truck, provided with an intervening adjusting device, substantially as set forth. 45

4. Equalizing mechanism for cars, consisting of tension members secured at their ends to the car-framing, at their opposite ends to the trucks, crossing each other and connected by a clamp rigidly supported from the car-body, substantially as set forth. 50

5. Equalizing mechanism for cars, consisting of rigid tension members connected at their ends to the car-framing and their other ends to the inner under side of the trucks, under supplementary members similarly connected to the car-framing and to the outer side of the trucks respectively, substantially as set forth. 55

6. Equalizing mechanism for cars, consisting of rigid tension members connected at their ends to the car-framing and their other ends to the inner under side of the trucks, under supplementary members similarly connected to the car-framing and to the other side of the trucks respectively, each of the 60 tension members having an adjusting device intermediate of its length, substantially as set forth. 70

7. In mechanism of the class described, a rigid tension member connected at one end 75 of the car-framing and at the other to a clevis in engagement with the king-bolt of the truck substantially as set forth.

In testimony whereof I affix my signature in presence of two witnesses.

CYRUS M. CARNAHAN.
